UNITED STATES PATENT OFFICE

ADAM B. FAHNESTOCK, OF MANHASSET, NEW YORK, ASSIGNEE, BY MESNE ASSIGNMENTS, TO THE STANDARD STOKER COMPANY INC., OF NEW YORK, N. Y., A CORPORATION OF DELAWARE

LOCOMOTIVE STOKER

Application filed August 9, 1926, Serial No. 127,985. Renewed August 23, 1929.

The invention relates to locomotive stokers of the scatter feed type, which deliver the fuel to the fire box of the locomotive above the level of the fire bed on the grate, over which bed it is spread by projecting and scattering means.

A practicable stoker for locomotives must be capable of use in connection with "run of mine" coal, which is of a wide range as to size, from quite fine particles up to lumps too large to be passed through conveying devices. These lumps must be reduced, and the entire mass conveyed in a necessarily tortuous path through conduits, within which operates the moving means. The reducing and transferring operations have resulted in a loss in economy, in that the smaller particles of fuel have been reduced to an almost impalpable fineness due to the grinding action to which they have been subjected in the crushing operation, by the transferring devices and by the impacting of masses of fuel at elbows and the like in the conduits. The loss sustained is due to the carrying into the flues and out of the stack, unconsumed, much of the finely comminuted fuel by the forced draft necessarily employed in locomotives. This loss is, of course, especially marked in stokers of the scatter feed type.

The object of the invention is to provide a simple, compact and direct acting mechanism for moving the fuel from the storage bin of the tender to the fire door of the fire box of the locomotive without subjecting the already present fine material to a grinding action due to the reduction of the larger lumps, and by avoiding abrupt and cramped turns in the path thru which it is conveyed. A further object is to provide for the location of the driving motor for the stoker mechanism upon the frame of the tender, in close proximity to the stoking device, whereby the mechanism may be driven in a simple manner and without the loss of power by reason of tortuous connections.

To this end, the invention consists in the parts and arrangement of parts as herein-after described and as illustrated in the accompanying drawings, in which

Fig. 1 is a detail longitudinal, vertical, central section thru the rear end of a locomotive and the forward end of the tender, the stoking mechanism being shown partly in elevation;

Fig. 2 is a detail plan section on the line 2—2 of Fig. 1;

Fig. 3 is a detail longitudinal, vertical section thru the forward part of the tender and the rearward portion of the stoker.

Fig. 4 is the side elevation of the rear portion of the stoking mechanism and the driving motor therefor, as applied to the tender, some parts being broken away.

Fig. 5 is a front view of the portion of the stoking mechanism carried by the tender; and

Fig. 6 is a plan view of certain of the power transmitting gearing.

The fire box of the locomotive is represented at 10; the back-head thereof at 11; the grate at 12, and the hand firing door opening in the back-head at 13.

The fuel bin of the tender is indicated at 14, its floor being composed at least in part of a plurality of channels, as 15, which extend forwardly from its rearward end to within a short distance of its front. Within each of these channels, there travels the upper turn of an endless sprocket chain 17, 80 which is carried by sprocket wheels 18, 19, one of which is located forward of the end of the channel 15, and the other back of the rearward end thereof and under the slope sheet 20. Each of these chains is provided with a plurality of spurs as 21, which project upwardly from the upper turn of the chain into the mass of coal. One of the sprocket wheels, as 18, is fixed upon a transfer shaft 22, provided with a ratchet wheel 23, with which cooperate pawls, as 24, carried by an oscillating casing 25, actuated by means of a link bar 26, carried by a swinging arm 27, and having a roller 28, which is engageable with the periphery of an eccentric 95 29 mounted on a shaft 30.

As the coal is carried forward by chains 17, the larger lumps are delivered between the fixed and oscillating jaws 31, 32, of a crusher, which reduce them to a proper size 100

for firing and from which they drop into a hopper 33. The finer particles of coal which are carried forward by chains 17 pass thru a riddle formed of bars 16 which project 5 backwardly from the fixed jaw 31 of the crusher, and enter the same hopper without experiencing the grinding action to which they would be subjected if mixed with the mass passing between the crusher jaws. A 10 pair of inclined guide plates 34 insure the delivery of all of the fuel into the hopper.

From the forward end of the hopper 33 and rigidly secured thereto leads a transfer conduit 35 within which the hopper is 15 housed a transferring screw 36 which delivers the fuel to a nozzle 37 projecting into the firing door opening 13, and occupying only the lower portion thereof.

The nozzle 37 is securely attached to the 20 back-head 11 as shown in Fig. 2, and the conduit 35 is connected with the nozzle by means of a ball joint 38 within one member of which it is sleeved as indicated at 39.

The floor 40 of the nozzle 37 projects thru 25 the opening 13 and constitutes a distributing plate from which the fuel is projected into the fire box by means of steam jets issuing from a plurality of nipples 41, extending upwardly thru it and supplied with steam by 30 means of a pipe 42 suitably connected with the steam chamber of the locomotive boiler.

To the under side of the hopper 33, there 35 is attached a backwardly projecting arm 43, which is loosely pivoted upon a stud 44, carried by the frame of the tender.

The conduit 35 is inclined upwardly toward its forward end and makes substantially a direct delivery from the hopper to the distributor plate 40, thereby avoiding 40 any sharp turns or angles which would tend to cause the impacting of the fuel and to pulverize it to a fineness which results in an un-economical operation. The described mounting, structure and connections of the hopper, 45 conduit and delivery nozzle compensate for any relative movements of the locomotive and tender due to unevenness and curvature of the railway track.

The mechanism as described is driven by 50 a motor, conventionally shown at 45, mounted on the frame of the tender and adjacent to its forward end. This motor may be of any desired type, a rotating motor being preferable because occupying but little space. Preference is expressed for the well known Dake 55 motor which while developing adequate power is very simple and compact. The shaft 46 of the motor carries a worm 47 meshing with a worm wheel 48 fixed upon a suitably 60 journaled shaft 49. The shaft 49 is connected by a universal joint 50 with a shaft 51 journaled in a bracket 52, mounted on the frame of the tender, the shaft carrying at its forward end a bevel gear 53 meshing with a 65 similar gear 53^a mounted on a transverse

shaft 54. A bevel gear 55 on the shaft 54 meshes with a bevel gear 56 fixed upon a shaft 57 journaled in a bracket 58 carried by the tender frame and connected at its forward end by means of a universal joint 59 with the rear end of the shaft of the conveyor screw 36.

A pinion 60, mounted on the shaft 54, 70 meshes with a gear 61 mounted on the shaft 30. The latter shaft is provided with a crank arm 62, connected by means of a pitman 63 with a crank arm 64, fixed upon the shaft 65, which carries the movable crusher jaw 32, the relative lengths of the crank arms 62 and 75 64 being such that a complete revolution of the shaft 30 causes the desired range of oscillation of the jaw.

The rate of fuel feed may be varied by varying the length of the advancing steps of the chains 17. For this purpose the casing 25, 80 which carries the pawls 24, is provided with an outwardly projecting arm 66, which on the downward movement of the link 26 by gravity, and the consequent backward movement of the pawls 24, encounters an adjustable limiting stop 67. This stop is in the form of a sliding bar carried by a bracket 68 and connected by a link 69 with a crank arm 70 fixed upon a vertical shaft 71 extending upwardly through the floor of the tender and carrying at its upper end a hand crank 72, suitable holding means conventionally shown at 73 being provided for retaining the shaft and stop bar 67 in adjusted positions. The arm 66 is downwardly curved, and, with the stop bar 67 in the position shown in Fig. 4, will 85 arrest the downward movement of the link 26 shortly after the swell of the eccentric 29 has passed beyond the roller 28, with the result that the next upward stroke of this link and consequently the advance movement of the pawls 24 is shortened. By withdrawing the stop bar 67 to its extreme limit, the outer end of the arm 66 will not come in contact with it until the lower end of the link 26 shall have 90 descended sufficiently to be engaged by the eccentric at its shortest radius, under which circumstances, the chains will be advanced by steps of maximum length, and consequently the rate of delivery of the fuel will be correspondingly increased.

The various transverse shafts are carried by a pair of plates 74, 75, which at their rearward ends rest upon the frame of the tender and at their forward ends are carried by the 95 brackets 52, only one of which is plainly shown.

The stoker as thus organized, while being of a high degree of efficiency, is simple of construction and requires for its operation but 100 little power. Its various elements are so related that they operate as a unitary structure and provide for the feeding of the fuel to the locomotive at such rate as the exigencies of the service may from time to time 105

require and in the condition essential to the highest degree of economy.

I claim as my invention:

1. In combination with a locomotive and a tender therefor, riddling and crushing means located at the forward end of the fuel bin of the locomotive tender, means for advancing fuel in the bin to the riddle and thence to the crusher means, a hopper for receiving fuel simultaneously from both the riddle and the crusher means, a distributor plate extending into the firebox of the locomotive, means for conveying fuel in a substantially straight line from said hopper to said plate, and means for distributing said fuel over the grates of said fire box.

2. In combination with a locomotive provided with a firebox having a backwall with a firing opening therein and a tender for said locomotive having a bin for the storage of fuel, conveying means on said tender for forwardly advancing the fuel, a distributor plate in said firing opening of the locomotive, a transfer conduit extending from a point directly beneath the forward end of said conveying means upwardly and forwardly to said distributor plate, the lower end of said transfer conduit being flexibly mounted and its upper end universally connected to the backwall of said firebox, said conduit being in communication at its lower portion with the conveying means and at its upper portion being in communication with said firing opening, the conveying means and said conduit being so related that the fuel drops by gravity directly from the conveying means to the conduit, transferring means within said conduit for moving the fuel therethrough upwardly and forwardly in a substantially straight course to said distributor plate, and means for distributing fuel over the fire.

3. In combination with a locomotive provided with a firebox having a backwall with a firing opening therein and a tender for said locomotive having a bin for the storage of the fuel, conveying means on said tender for forwardly advancing the fuel, a fuel distributor in said firing opening of the locomotive, an inclined transfer conduit extending from a point immediately beneath the forward end of said conveying means upwardly and forwardly to said distributor, a helical screw in said conduit, said transfer conduit being in communication at its lower portion with said conveying means and at its upper end of itself opening directly into said firing opening, the adjacent ends of the conveying means and transfer conduit so related that the fuel is fed from the conveying means to and transversely of the transfer conduit, the fuel spilling by gravity from said means in loose form directly on to said helical screw at a point below said distributor, said screw transferring the fuel in a constant upward and forward direction in a substantially

straight course through said conduit to the distributor, the adjacent ends of the conveying means, and the screw within the transfer conduit being free from universal connections within the path of the course of flow of the fuel.

4. In combination with a locomotive provided with a firebox having a firing opening in its backwall and a tender behind the locomotive provided with a fuel bin, a stoker including a distributor at the firing opening, a conveyor communicating with the bin and delivering fuel loosely at a point below the firing opening, and an upwardly inclined screw conveyor receiving the fuel in loose form from the first conveyor and conveying it substantially straight from the point of reception into the firing opening and delivering it endwise from its forward end toward the distributor, the passage for the fuel between the conveyors permitting unrestricted flow of fuel.

In testimony whereof I affix my signature.

ADAM B. FAHNESTOCK.
